UNITED STATES PATENT OFFICE.

EDWARD R. INMAN, OF FRANKLIN, PENNSYLVANIA.

BRAKE-BEAM.

No. 834,524.

Specification of Letters Patent.

Patented Oct. 30, 1906.

Application filed July 26, 1905. Serial No. 271,305.

To all whom it may concern:

Be it known that I, EDWARD R. INMAN, a citizen of the United States, residing at Franklin, in the county of Venango and State of Pennsylvania, have invented certain new and useful Improvements in Brake-Beams, of which the following is a specification, reference being had therein to the accompanying drawings.

10 My invention relates to improvements in brake-beams for railway-brakes and will be fully understood from the following specification, reference being had to the accompanying drawings, which form a part of this specification, and in which—

15 Figure 1 is a plan view of my brake-beam. Fig. 2 is an end view of same. Fig. 3 is a rear elevation. Fig. 4 is an enlarged section on line 4-4 of Fig. 1. Fig. 5 is a front view of 20 the central portion of the beam at and near the fulcrum. Fig. 6 is a section of the beam at 6 6 of Fig. 3.

25 My invention lies in the peculiar form of the cross-section of my beam and its particular adaptation to withstand the vertical strain due to the impingement of the shoe upon the periphery of the car-wheel when the 30 brakes are set and in the manner of reinforcing it to sustain the pressure at the center of 35 the beam, due to setting the brakes.

The specific form of a cross-section of my beam proper may aptly be described as **W**-shaped, with the junctional points I and J well rounded and the outer legs L forming 35 the major portion of a semicircle, as illustrated in Fig. 6, wherein the circle of which said legs form a portion is shown in dotted lines.

40 In mounting the brake-heads and fulcrum upon my beam they are preferably so located that the edges E are in compression and the points J are in tension, which arrangement brings the outer channels C to the rear and the intermediate channel C' to the front or 45 brake-head side of the beam, as is clearly illustrated by the section at Fig. 4.

45 The manner of reinforcing my beam is substantially as follows: The front fulcrum-block 1 is provided upon two opposite sides 50 with the extension or bolster 2, which is **V**-shaped in cross-section, extends longitudinally of the beam, and fits closely with the channel C'. The rear fulcrum-block 3 is provided upon two opposite sides with the double bolsters 4 4, which also extend longitudinally of the beam and occupy the channels C,

each bolster bearing upon the bottom of the channel which it occupies. Bolster 2 may be riveted to the beam, if this construction should be found more conducive to rigidity; 60 but I do not confine myself to this feature of construction, and be it understood that either the front or the rear bolsters could be omitted without departing from the spirit of my invention.

65 The fulcrum 5 is provided with the head 6 and the stem 7, (shown in dotted lines,) and both fulcrum-blocks and the beam are provided with aligned holes through which stem 7 extends. The outer end of stem 7 is threaded for the reception of a nut 8, and when said nut is firmly screwed up the beam is securely clamped between the fulcrum-blocks and the bolsters form a rigid reinforcement which prevents any appreciable deflection for the 70 amount of strain which the beam is practically required to withstand.

75 In nearly all brake-beams in use at the present day provision has in some way been made to sustain the strain applied at the fulcrum in setting the brakes, but a strain transverse to this is caused by the impingement of shoe upon the periphery of the car-wheel, and this strain, which is a vertical one, has thus far been almost wholly disregarded in 80 the construction of brake-beams. It will be noted that my beam is especially designed to withstand this strain, the vertical axis of it being greater than the transverse axis, and the reinforcements at the center assist some- 85 what in sustaining this strain.

90 The precise manner of attaching the brake-heads to my beam is immaterial; but in the drawings, more especially in Fig. 2, I have shown a head having a recess with concave 95 walls to fit the convex face L' of the legs L of the beam and a lug c' to enter the channel C', and upon the opposite side of the beam is placed a block 9, having the double lugs c c, which conform to and enter the channel C C. 100 A bolt 10 is then passed through all three members, and the head is thus firmly secured to the beam.

Having thus described my invention, what I claim as new, and desire to secure by Letters Patent, is—

110 1. A brake-beam of **W**-shaped cross-section, having rounded junctional points and the outer legs forming the major portion of a semicircle.

2. A brake-beam of **W**-shaped cross-section, in combination with the fulcrum-blocks

located centrally of said beam, there being bolsters upon said blocks which extend longitudinally of said beam and seat in the channels thereof.

5. 3. The combination with a brake-beam, of fulcrum-blocks, located upon the tension and compression sides of said beam, said blocks being provided with bolsters which coöperate to reinforce the beam against the strains of tension and compression.

4. The combination with a brake-beam, of means centrally located upon each side thereof, to reinforce said beam against both the strains of tension and compression.

5. The combination with a brake-beam, of 15 a bolster which extends longitudinally of the beam and bears upon the tension side thereof, and a supplementary bolster which extends longitudinally of the beam and bears against the compression side thereof, substantially as described. 20

In testimony whereof I affix my signature in presence of two witnesses.

EDWARD R. INMAN.
